UNITED STATES PATENT OFFICE.

JOHN M. LARSON, OF CHICAGO, ILLINOIS, ASSIGNOR TO NATIONAL REGULATOR COMPANY, OF CHICAGO, ILLINOIS, A CORPORATION OF ILLINOIS.

REGULATOR FOR EXPANSION-VALVES.

1,146,803.

Specification of Letters Patent.

Patented July 20, 1915.

Application filed August 8, 1912. Serial No. 714,129.

To all whom it may concern:

Be it known that I, JOHN M. LARSON, a citizen of the United States, residing at Chicago, in the county of Cook and State 5 of Illinois, have invented new and useful Improvements in Regulators for Expansion-Valves, of which the following is a full, clear, concise, and exact description, reference being had to the accompanying drawing, forming a part of this specification.

My invention relates to improvements in expansion valves, and has for its object the production of a valve that can be adapted for use in connection with either air, gas or 15 water, and in various industries.

A further object is the production of a device in which the expansible member is so formed as to operate efficiently in either direction after the valve is closed without 20 deterioration or injury, and one that is not liable to breakage through variation of temperature.

A further object is the production of a device in which it is not necessary to submit 25 the inside of the cylinders or jackets to great pressure.

A further object is the production of a device of simple construction that can be cheaply manufactured, and one that is not 30 liable to get out of order.

These, and such other objects as may hereinafter appear, are obtained by my device, embodiments of which are illustrated in the accompanying drawings, in which—

Figure 1 represents a plan view of my device in position ready for use, the operative portions being shown in sections. Fig. 2 represents a sectional detail, showing a modification of a portion of Fig. 1.

Like numerals of reference indicate like parts in the several figures of the drawing.

This application is an improvement on the invention described in my application Serial No. 699,696, filed May 25, 1912.

Referring now to the drawings, A represents my improved device connected at the top through the medium of a pipe 3 and L 4 with the top of a cylinder or jacket 5. A similar L 6 is connected to the bottom of the jacket or cylinder, and to this is connected a pipe or coupling 7 screwed into the lower portion of my device. A supply pipe 8 is screwed into the opposite end of my device, through which cold water is brought from 55 any desired source of supply. A main dis-

charge pipe 9 is in open communication with the interior 10 of the threaded T 11 and the pipe 3 communicates with the interior 12 of the threaded T 13. Between the T's 11 and 13 is mounted a tube 14 containing the 60 expansible valve stem 15, shown as split at 16 into two separated portions 15^a and 15^b. At the top the expansible valve stem 15 is screwed into the enlarged end 17 of the screw-bolt 18, on which is mounted an indicator 19, 65 while the flanged head 20, having a dial (not shown) on its upper face, surrounds the member 18 and is screwed into the top of the T 13. A suitable housing 21 covers the indicator and dial and prevents tampering with 70 the device.

The expansion valve proper is mounted on an extension of the lower end of the stem 15, and within the casing 22 screwed on the lower end of the T 11 at 23 are a pair of 75 washers 24 and 24^a, between which is mounted a large rubber washer 25, the metal washers 24 and 24^a being smaller than the inner diameter of the casting 22, and the rubber washer 25 having enlarged or spread ends 80 26 adapted to fit tightly between the outer edges of the washers 24 and the inner face of the casting 22, thus preventing any leakage. Below the washers 24 is an extension rod 27, on the end of which is mounted the 85 valve proper 28, a coil spring 29 being inserted between the valve and the washers 24.

The casting 22 is enlarged, as shown at 30, its enlarged inner face 31 forming a seat for the valve 28. Secured to the bottom of 90 the casting 22 is a diaphragm valve casing comprising an upper member 32 and a lower member 33 secured together, as shown at 34, and having mounted within its interior a diaphragm 35 dividing the interior into 95 an upper chamber 36 and a lower chamber 37. This lower chamber communicates with the interior of the primary valve casting 38, forming the base of the device A and into which the supply pipe 8 and the discharge pipe 7 therefrom communicate. The interior of this member 33 is divided by a wall 39 into an upper chamber 40 and a lower chamber 41. Communication between these chambers is regulated by means of a 100 valve 42 fitting within an opening 43 in the wall 39, and seating against the valve seat 42^a on said wall.

The diaphragm 35 is connected to the valve 42 by means of a rod or stem 44, said 110

stem having a passage 45 extending entirely through the same and making communication between the lower chamber 41 and the upper diaphragm chamber 36. It will be noted that the lower surface of the valve 42 is of much less area than the upper surface of the diaphragm 35.

5 The lower diaphragm chamber 37 and the supplemental chamber 46, surrounding the rod 27 above the valve 28, are connected through the medium of a connecting pipe 47. The lower end of this connecting pipe screws into an opening 48 in the lower casting 33 and into an opening 49 in the upper member 22.

10 In Fig. 2 I have shown two alternative constructions to take the place of the diaphragm and chambers, substituting therefor a cylinder 50, within which the rod 44 is replaced by a piston-rod 51 having an opening 52 and on the end of which is mounted a piston-head 53, dividing the cylinder into upper and lower chambers 54—55, corresponding to the chambers 36—37.

15 A tight fit between the piston-head and the interior of the cylinder is effected by means of a pair of metal rings 56 or these rings may be omitted and a rubber disk or washer 57 placed on the top of the cylinder head and shown in dotted lines. In the event that my device is used in connection with steam, I prefer to use the piston-head with a piston-ring thereon, between the rods 27 and the stem 15.

20 25 In order to maintain a constant circulation through the entire system, regardless of the relative positions of the valves, I provide within the wall 39 a small vent port or leak 58, permitting the passage of fluid from the supply pipe 8 into the cylinder or container 5.

30 Referring now to the operation of my device, let it be considered that the interior of the cylinder or jacket 5 is filled with water at any degree of temperature, and the indicator is set to permit the valve to open at a slightly increased temperature, the valve 42 being closed. Prior to this time the pressure transmitted through the fluid in the pipe 8 has forced the fluid into the chamber 40 through the pipe 7 and into and filling the jacket and the entire system, and has at the same time been forced up through the passage 45 into the upper diaphragm chamber 36. When the diaphragm chamber is full the enlarged area of the diaphragm 35 forces the valve 42 downwardly against its seat 42^a, shutting off the passage of any more fluid into the chamber 40. The valve 28 being seated against its seat 31, no portion of the fluid contained within the system below the diaphragm itself can pass through the by-pass 47 and into the chamber 46. At the same time, however, sufficient fluid leaks through the vent 58 into the sys-

tem to cause a slow circulation through the jacket pipe 3, the interior of the tube 14, and out through the general discharge pipe 9. This state of affairs continues until the temperature within the system has been raised 70 to such a point as to affect the valve stem 15 sufficiently to cause it to expand or lengthen and forces the valve 28 away from its seat 31. The moment that this occurs, open communication is afforded between the 75 upper and lower diaphragm chambers through the by-pass 47, the fluid from the chamber 36 passing up through the chamber 46 and by-pass 47 and into the lower diaphragm chamber and into the main system. 80 This operation relieves the pressure on the upper face of the diaphragm 35, and when this pressure is sufficiently reduced, the normal pressure exerted through the pipe 8 on the lower portion of the valve 42 is sufficient to raise the valve 42 and permit a fresh supply of cool fluid to pass into the system. When this cool fluid comes in contact with the valve stem 15 it causes it to contract and close the valve 28 against its seat 31, thereby 85 closing communication between the upper and lower diaphragm chambers, on the happening of which event the fluid passing through the passage 45 in the rod 44 again fills the upper diaphragm chamber 36 until 90 the pressure reaches normal, closing the valve 42 into its initial position. In the event that it is desired to store the hot water or the surplus water from the container, or to force it to any considerable 95 height, it may often happen that the pressure in the upper portion of the system will approach that of the initial pressure of the fluid being supplied to the system. If this condition arises, the pressure above and below the diaphragm 35 will be either equal 100 or so nearly equal as to prevent the operation of the device. In order to overcome what is practically a dead center in the system, I provide a spring 59 seated with 105 in the upper chamber 36 and resting normally on the top of the diaphragm, or the diaphragm nut 60. The spring being normal under tension, serves to prevent any 110 equalization of pressure on either side of the system. While I have described this operation as consisting in the periodical opening and closing of the valve, it is evident that the parts may be so adjusted as to afford 115 substantially continuous operation of my device between limited ranges of temperature, the valves opening and closing to a very slight degree, amounting practically to a pulsatory motion instead of an intermittent one. 120 In a great many cases where a device of this character is needed, the parts are subject to very high pressure, and it becomes a serious question whether or not to permit such a pressure upon the interior of the 125 130

cylinder, jacket or container. By the use of my device, however, all extreme variations of pressure are avoided, but at all times a sufficient pressure is supplied to maintain 5 the fluid in circulation and at the required degree of heat necessary to secure the highest efficiency.

My device is especially useful in large installations that handle upward of two 10 thousand gallons per hour. It is, of course, clearly evident that slight modifications of parts shown may be substituted without in any way departing from the spirit of my invention.

15 I claim:

1. In a system of the class described, the combination with a container, an expansion valve chamber, an expansion valve mounted therein, means for maintaining a uniform 20 circulation of fluid within predetermined ranges of temperature through said container, and means for introducing an increased supply of fluid when the fluid within said system has reached a predetermined 25 temperature, said means comprising a supplemental valve outside of said container, with means whereby said expansion valve causes said supplemental valve to control the ingress of fluid into and the egress of fluid 30 out of said system.

2. In a system of the class described, the combination with a container, an expansion valve chamber, an expansion valve mounted therein, means for maintaining a uniform 35 circulation of fluid within predetermined ranges of temperature through said container, and means for introducing an increased supply of fluid when the fluid within said system has reached a predetermined 40 temperature, said means comprising a supplemental diaphragm valve outside of said container, with means whereby said expansion valve causes said supplemental valve to control the ingress of fluid into and the 45 egress of fluid out of said system.

3. In a system of the class described, a container and means for maintaining a constantly changing flow of fluid through said container at a temperature defined by predetermined 50 ranges, an expansion valve casing divided into an upper and lower chamber, an expansion rod passing through said chambers, a valve mounted on the lower end of said rod, a supplemental valve casing 55 mounted below said expansion valve, a supplemental valve mounted therein and controlling the inflow of fluid within the system, and means whereby the operation of said expansion valve operates said supplemental valve.

4. In a system of the class described, a container and means for maintaining a constantly changing flow of fluid through said container at a temperature defined by predetermined 60 ranges, an expansion valve cas-

ing divided into an upper and lower chamber, an expansion rod passing through said chambers, a valve mounted on the lower end of said rod, a supplemental valve casing mounted below said expansion valve, a supplemental valve mounted therein and controlling the inflow of fluid within the system, and means whereby the operation of said expansion valve operates said supplemental valve, said means including pipe connections between said lower chamber and the interior of said supplemental valve casing. 70

5. In a system of the class described, a container and means for maintaining a constantly changing flow of fluid through said container at a temperature defined by predetermined ranges, an expansion valve casing divided into an upper and lower chamber, an expansion rod passing through said chamber, a valve mounted on the lower end of said rod, a supplemental valve casing mounted below said expansion valve, a diaphragm dividing the interior of said casing into an upper and lower diaphragm chamber, a supplemental valve controlling an opening between said lower diaphragm chamber and source of supply, and means whereby the operation of said expansion valve regulates the movements of said supplemental valve. 95

6. In a system of the class described, a container and means for maintaining a constantly changing flow of fluid through said container at a temperature defined by predetermined ranges, an expansion valve casing divided into an upper and lower chamber, an expansion rod passing through said chamber, a valve mounted on the lower end of said rod, a supplemental valve casing mounted below said expansion valve, a diaphragm dividing the interior of said casing into an upper and lower diaphragm chamber, a valve mounted below and secured to said diaphragm and controlling an opening between said diaphragm chamber and the source of fluid supply, pipe connections between said lower expansion valve chamber and the lower diaphragm chamber, whereby the movement of said expansion valve controls the admission of fluid into the system. 100

7. In a system of the class described, a container and means for maintaining a constantly changing flow of fluid through said container at a temperature defined by predetermined ranges, an expansion valve casing divided into an upper and lower chamber, an expansion rod passing through said chamber, a valve mounted on the lower end of said rod, a supplemental valve casing 115 mounted below said expansion valve, a diaphragm dividing the interior of said casing into an upper and lower diaphragm chamber, a hollow rod mounted on the center of said diaphragm, a valve secured to the lower 120

125

130

1
end of said rod and controlling an opening 25
between said diaphragm chamber and the
source of fluid supply, pipe connections be-
tween said lower expansion valve chamber
5 and the lower diaphragm chamber, whereby
the movement of said expansion valve con-
trols the admission of fluid into the system.

8. In a system of the class described, the
combination with a container, an expansion
10 valve chamber, an expansion valve mounted
therein, means for maintaining a uniform
circulation of fluid within predetermined
ranges of temperature through said con-
tainer, and means for introducing a fresh
15 supply of fluid when the fluid within said
system has reached a predetermined tem-
perature, said means comprising a supple-
mental spring controlled diaphragm valve
20 outside of said container, with means where-
by said expansion valve causes said supple-
mental valve to control the ingress of an in-
creased supply of fluid into and the egress
of fluid out of said system.

9. In a system of the class described, a con-

25 tainer and means for maintaining a con-
stantly changing flow of fluid through said
container at a temperature defined by pre-
determined ranges, an expansion valve cas-
ing divided into an upper and lower cham-
ber, an expansion rod passing through said 30
chamber, a valve mounted on the lower end
of said rod, a supplemental valve casing
mounted below said expansion valve, a
spring-pressed diaphragm dividing the in-
terior of said casing into an upper and lower 35
diaphragm chamber, a supplemental valve
controlling an opening between said lower
diaphragm chamber and source of supply,
and means whereby the operation of said
expansion valve regulates the movements of 40
said supplemental valve.

In witness whereof, I have hereunto sub-
scribed my name in the presence of two wit-
nesses.

JOHN M. LARSON.
